UNITED STATES PATENT OFFICE.

EDGAR E. PHINNEY, OF WEST ORANGE, NEW JERSEY, ASSIGNOR TO MONROE CALCULATING MACHINE COMPANY, OF ORANGE, NEW JERSEY, A CORPORATION OF NEW YORK.

CARRIAGE-LOCK FOR CALCULATING-MACHINES.

1,384,634.

Specification of Letters Patent. Patented July 12, 1921.

Application filed February 7, 1920, Serial No. 356,882. Renewed May 12, 1921. Serial No. 468,978.

To all whom it may concern:

Be it known that I, EDGAR E. PHINNEY, a citizen of the United States, resident of West Orange, in the county of Essex and State of New Jersey, have made a certain new and useful Invention in Carriage-Lock for Calculating-Machines; and I declare the following to be a full, clear, and exact description of the same, such as will enable others skilled in the art to which it appertains to make and use the invention, reference being had to the accompanying drawings, and to letters or figures of reference marked thereon, which form a part of this specification.

15 Figure 1 is sectional view of the invention, on the line 1—1, Fig. 2.

Fig. 2 is a front view, with parts broken away, the carriage being shown in normal position.

20 Fig. 3 is a view similar to the right-hand end of Fig. 1, the carriage being shown as raised.

Fig. 4 is a view similar to the left-hand end of Fig. 2, the carriage being shown as 25 raised.

The invention has relation to means for preventing displacement of the shiftable carriage of a calculating machine during a registering operation, being particularly applicable to a machine of the type shown in the reissue patents to Baldwin, No. 13,841, and No. 13,842.

The object of the invention is to provide a locking means of this character which will 35 render it impossible to operate the machine unless the carriage is properly positioned, with the gears carried thereby fully meshed with the corresponding gears on the frame.

The invention consists in the novel construction and combinations of parts, as hereinafter set forth.

In the accompanying drawings, illustrating the invention, the numeral 1 designates the frame of the machine, and 2 an endwise shiftable carriage, pivoted upon said frame at 59, said carriage having mounted thereupon a series of numeral or registering dials 13, each carrying a gear. A series of intermediate gears 12 is mounted upon frame 1, in position to mesh with the gears of the dials 13, these intermediate gears being operated by primary selecting elements 5, mounted on rotary shaft 4, and by carry teeth *j*, mounted upon shaft 73, as described

in the above-mentioned reissue patent to 55 Baldwin, No. 13,841. The shafts 4 and 73 are rotated in either direction, through gear connection with crank handle 3, to transmit clockwise or counter-clockwise movement to the registering dials, through the 60 gears 12, according to the nature of the problem to be solved.

The carriage is movable to shift the series of registering dials thereon with relation to the series of intermediate gears 12, as described in the Reissue Patent No. 13,842, hereinbefore mentioned, the carriage being raised upon pivot 59 to disengage the respective gears, laterally shifted and allowed to seat in adjusted position through gravity. 70 This is accomplished by means of a rotatable rod 61, having opposite crank arms 64, engaging seats 65 of an element of the carriage frame located opposite pivot 59. The engagement of the opposite arms 64 with the 75 seats 65 will prevent endwise movement of the carriage, so long as it remains seated in normal position.

The carriage positioning and locking means comprises a disk *d*, rigidly mounted 80 upon an element of the operating means, herein shown as the shaft 4 of the primary selecting elements. This disk is notched circumferentially at *e*, the lateral walls of the notch lying normally upon opposite sides of 85 a beveled tooth or projection *b* of a lever *c*, pivoted to the frame at *i* and extending below shaft 4. The free end of lever *c* has pivoted thereto an extension arm *a*, terminating at its upper end in a hooked head *a'*, 90 normally engaging a horizontal ledge or shoulder *h* of the carriage frame.

When the carriage is raised upon its pivot, lever *c* and its extension arm *a* will be raised freely therewith, tooth *b* entering the notch 95 of disk *d*.

Upon rotation of the crank handle 3 in either direction, the rotative movement of shaft 4 will bring a wall of notch *e* into engagement with tooth *h*, should the lever *c* be 100 in raised position, and will force said lever downwardly. Should the carriage not be properly seated, extension *a*, through its hooked head *a'*, will now force it into proper position, the downward pressure acting, 105 through crank rod 61, to complete the endwise shifting movement of said carriage, to bring the gears of the registering dials fully

in mesh with the gears 12. The peripheral face *q* of disk *d* will now be opposite tooth *b*, thereby preventing the raising of the lever and carriage until the completion of the registering operation, when the notch *e* will again come opposite tooth *b*. Obviously, the registering movement cannot occur while the carriage is raised, as the tooth is held in the notch of disk *d*.

10 Provision is made for manually unlocking the carriage at any time, by allowing a pivotal movement of extension *a* upon lever *c*, so that the hooked head *a'* may be grasped and pulled out of engagement with shoulder *h* of the carriage, against the tension of a spring *f* of said extension.

I claim:

1. In a calculating machine, a frame, an endwise-shiftable carriage, registering dials thereon, gears upon said dials, driving gears mounted on said frame, means for operating said driving gears, and locking means preventing movement of the operating means whenever the gears of said dials are out of mesh with said driving gears.

2. In a calculating machine, a frame, an endwise-shiftable carriage, registering dials thereon, gears upon said dials, driving gears mounted on said frame, means for operating said driving gears, and means actuated by the operating means for shifting said carriage endwise to bring the gears of said dials into mesh with said driving gears.

3. In a calculating machine, a frame, an endwise-shiftable pivoted carriage, registering dials thereon, gears upon said dials, driving gears mounted on said frame, means for operating said driving gears, and means actuated by the operating means for moving said carriage upon its pivot to bring the gears of said dials into mesh with said driving gears.

4. In a calculating machine, a frame, an endwise-shiftable carriage, registering dials thereon, gears upon said dials, driving gears mounted on said frame and meshing with the gears of said dials, means for operating said driving gears, means for disengaging said meshed gears and for shifting the carriage, and means actuated by the operating means for reengaging said gears.

5. In a calculating machine, a frame, an endwise-shiftable carriage, registering dials thereon, gears upon said dials, driving gears mounted on said frame, means for operating said driving gears, and means for locking the carriage against movement during the operation of said driving gears, said locking means preventing movement of the operating means whenever the gears of said dials are out of mesh with said driving gears.

6. In a calculating machine, a frame, an endwise-shiftable carriage, registering dials thereon, gears upon said dials, driving gears mounted on said frame, means for operating

said driving gears, and means preventing any simultaneous movement of said carriage and of said driving gears.

7. In a calculating machine, a frame, an endwise-shiftable carriage, registering dials thereon, gears upon said dials, driving gears on said frame, means for operating said driving gears, and means for locking the carriage against movement during the operation of said driving gears including a member mounted on said frame, engaging the carriage and normally movable in the movement of the carriage, and a member coöperable with said first-named member to effect the locking.

8. In a calculating machine, a frame, an endwise-shiftable carriage, registering dials thereon, gears upon said dials, driving gears on said frame, means for operating said driving gears, and means for locking the carriage against movement during the operation of said driving gears including a lever mounted on said frame, engaging the carriage and normally movable in the movement of the carriage, and a rotary member coöperable with said lever to effect the locking.

9. In a calculating machine, a frame, an endwise-shiftable pivoted carriage, registering dials thereon, gears upon said dials, driving gears on said frame, means for operating said driving gears including a rotary shaft, and means for locking the carriage against movement during the operation of said driving gears including a compound lever mounted on said frame, engaging the carriage, normally movable in the movement of the carriage and having a projection, and a rotary disk upon said shaft having a circumferential notch normally overlying said projection, the circumferential surface of said disk being engageable with said projection to effect the locking.

10. In a calculating machine, a frame, an endwise-shiftable pivoted carriage having a horizontal ledge and registering dials, gears upon said dials, driving gears on said frame, means for operating said driving gears including a rotary shaft, and means for locking the carriage against movement during the operation of said driving gears including a lever having a projection, said lever having an extension arm pivoted thereto and provided with an upper hooked end normally engaging said ledge and with a tail end having a spring connection, said lever and extension arm being movable in the movement of the carriage, and a rotary disk upon said shaft having a circumferential notch normally overlying said projection, the circumferential surface of said disk being engageable with said projection to effect the locking.

11. In a calculating machine, a frame, an endwise-shiftable carriage, registering dials

thereon, gears upon said dials, driving gears mounted on said frame, means for operating said driving gears, a lock lever mounted on said frame, lying in the path of shifting movement of said carriage and movable from said path in two directions, a coöperating lock member adapted to prevent movement of said lever in one direction during the movement of said driving gears, and a spring resisting movement of said lever in the other direction.

5 In testimony whereof I affix my signature in presence of two witnesses.

EDGAR E. PHINNEY.
